(57) **CLAIM**

The ornamental design for an outdoor unit for air conditioner as shown and described.

DESCRIPTION

1. Outdoor unit for air conditioner

1.1 : Front perspective view

1.2 : Back perspective view

1.3 : Front

1.4 : Back

1.5 : Left

1.6 : Right

1.7 : Top

1.8 : Bottom

The characteristic features of the design lie in the shape; the broken lines shown in the reproductions depict portions of the outdoor unit for air conditioner and form no part of the claimed design; the shading lines are used to show the surface of the claimed design and do not represent its surface ornamentation.

1 Claim, 8 Drawing Sheets
